UNITED STATES PATENT OFFICE.

JOHN E. FOLEY, OF PONTIAC, MICHIGAN.

VEHICLE-HUB.

SPECIFICATION forming part of Letters Patent No. 702,548, dated June 17, 1902.

Application filed October 16, 1901. Serial No. 78,776. (No model.)

To all whom it may concern:

Be it known that I, JOHN E. FOLEY, a citizen of the United States, residing at Pontiac, county of Oakland, State of Michigan, have 5 invented a certain new and useful Improvement in Vehicle-Hubs; and I declare the following to be a full, clear, and exact description of the invention, such as will enable others skilled in the art to which it pertains to 10 make and use the same, reference being had to the accompanying drawings, which form a part of this specification.

My invention relates to an improvement in vehicle-hubs, shown in the accompanying 15 drawings, and more particularly pointed out in the specification and claims.

In the drawings, Figure 1 is a sectional view through the hub and its encircling collar or band. Fig. 2 is a detail sectional view showing a variation of the means for securing the 20 collars to the hub. Fig. 3 is a similar view of another variation.

The object of my invention is to provide a simple and effective means for securing the 25 collars or bands to the wood hub of a vehicle-wheel and in other matters of detail herein-after referred to.

Referring to the letters of reference shown in the drawings, A is the wooden hub; BB, the 30 collars or bands.

CC are metal plugs set in recesses cut in the wooden hub.

DD are screws entering the plugs set in the hub through holes in the collars, thereby 35 engaging the bands to the hub. In the variation shown in Fig. 2 holes are bored at suitable points around the periphery of the hub, and corresponding holes are drilled in the bands encircling the hub of smaller diameter. After 40 the bands are placed in position lead is poured in the several holes, filling the cavities. It will be seen that by boring a larger hole in the wood than in the band and then filling the entire cavity there can be no possibility 45 of the plug working out, while at the same time it effectually holds the collar in position.

In the variation shown in Fig. 3 the plug is screw-threaded on the outside, so that if it becomes necessary to remove the collars at any 50 time they can be taken off by removing the

screws D, and in this construction there is no possibility of the plugs dropping out when the collar is taken off.

In constructing the collars I prefer to form the inner edge tapering, or what is commonly known as a "knife-edge," in order that the collar and wooden portion may be flush on the inside without cutting a shoulder in the wood, which I have found in practice has a tendency to chip. 60

In place of pouring lead in the cavities shown in the variation in Fig. 2 iron or steel plugs may be employed, having a contracted projecting portion similar in shape to the lead plug over which the bands are forced, the contracted ends of the plugs entering the holes in the bands. 65

Having thus described my invention, what I claim is—

1. In a vehicle-hub, a wood portion, metallic 70 plugs recessed in said wood portion and tapped to receive a screw, collars encircling said wood portion and the plugs, said collars provided with holes adapted to register with the holes in the plugs, and screws for engaging the collars with the plugs, substantially as described. 75

2. In a vehicle-hub, a wood portion, metallic 80 plugs having a screw-threaded engagement with said wood portion, the ends flush with the surface of the wood portion, said plugs tapped to receive a screw, collars encircling 85 said wood portion and the plugs and provided with holes registering with the holes tapped in the plugs, and screws to engage the collars with the plugs, substantially as described. 85

3. In a vehicle-hub, a wood portion, metallic 90 plugs recessed in said wood portion and tapped to receive a screw, collars to encircle said wood portion and plugs provided with holes registering with the holes in the plugs, said 95 collar formed with a knife-edge on the inside so as to form a flush joint with the wood and screws to engage the collar to the plugs, substantially as described.

In testimony whereof I sign this specification in presence of two witnesses.

JOHN E. FOLEY.
